UNITED STATES PATENT OFFICE

JAMES J. SUNDAY, OF DETROIT, MICHIGAN, ASSIGNOR, BY MESNE ASSIGNMENTS, TO
KELCH VENTILATING HEATER COMPANY, A CORPORATION OF MICHIGAN

HEATER FOR AUTOMOBILES

Application filed September 11, 1925. Serial No. 55,847.

This invention relates generally to heaters for automobiles and consists of certain novel features of construction, combinations and arrangements of parts as will be more fully described and particularly pointed out in the appended claims.

In the accompanying drawing:

Figure 1 is a fragmentary side elevation of a motor vehicle with a heater embodying my invention attached thereto;

Figure 2 is an enlarged vertical longitudinal sectional view through the heater;

Figure 3 is a cross sectional view taken on the line 3—3 of Figure 2.

Referring now to the drawing, the numeral 1 designates an exhaust conduit of an automobile having a section 2 that preferably constitutes the shell or casing of my heater. As shown, this section 2 preferably has a larger diameter than the exhaust conduit ordinarily provided and is preferably formed of several lengths of tubing which are joined together.

In order that fresh air from the atmosphere may be heated thoroughly by the exhaust gases passing through the conduit 1 without building up back pressure on the engine, I preferably provide a suitable shell that has a section 3 located within and preferably concentric with the shell section 2. As shown, the forward end of this section 3 is connected to a tube 4 that extends through the shell section 2 and terminates adjacent to the usual fan 5 of the engine, while the rear end of the section 3 is connected to a tube 6 that extends through the shell section 2 and leads to a suitable register 7 located preferably in the floor 8 of the automobile.

In use, the air from the atmosphere will pass through the tube 4 into the shell 3 where it will be heated thoroughly by the exhaust gases passing through the shell section 2 and will then pass upwardly through the tube 6 to the floor register 7.

Thus, from the foregoing description, it will be apparent that I have provided an extremely simple form of heater that is composed of a minimum number of parts which may be manufactured at a comparatively low cost and may be easily and quickly assembled.

Moreover, the air passing through the shell

3 will be intensely heated due to its location within the shell section 2. As this shell 3 is preferably concentric with the section 2, all surfaces of the shell 3 will be subjected to the exhaust gases passing through the shell section 2, hence the maximum heat will be obtained. Inasmuch as the diameter of the shell section 2 is enlarged it will also be readily apparent that the exhaust gases will have a free and unobstructed passage around the shell 3, hence back pressure will not be built up on the engine. Moreover, the arrangement is such that the exhaust gases cannot escape from the shell section 2 and into the tube 6 which conveys the air to the register.

Should the tube 6 work loose in the shell section 2, the exhaust gases will pass upwardly around the tube to the atmosphere.

While it is believed that from the foregoing description the nature and advantages of my invention are readily apparent, I desire to have it understood that I do not limit myself to what is herein shown and described and that such changes may be resorted to when desired as fall within the scope of what is claimed.

What I claim as my invention is:

1. A heating apparatus for an automobile body comprising a tube having its opposite ends attachable to an automobile engine exhaust manifold and exhaust muffler respectively and provided throughout substantially its entire length with a cross sectional area that is slightly larger than the cross sectional area of an ordinary exhaust conduit whereby the exhaust gases from an automobile engine may flow into and through the tube and be utilized therein as a heating medium, said tube being imperforate except for four openings, two of said openings being at one end of said tube and constituting inlets for air and exhaust gases respectively, and the other two openings being at the other end of said tube and constituting outlet openings for air and exhaust gases respectively, and means open at its opposite ends to the atmosphere for conveying air from the atmosphere into the tube aforesaid to be heated by the en-

- gine exhaust gases therein, and thence from the tube to the atmosphere within a vehicle body, said means including a tubular conduit having three sections arranged end to end, the intermediate section of said conduit being entirely within and extending longitudinally of said tube, and the two other sections constituting a fresh air inlet and a hot air outlet respectively for said intermediate section and extending through the air inlet and outlet openings aforesaid in said tube, the inlet section being open at its forward end to receive air from the atmosphere and having the portion thereof within the tube extending at a substantially obtuse angle with respect to the longitudinal median line of said tube so that the exhaust gases flowing through the tube from the engine will be deflected but not materially retarded around the intermediate section within said tube to heat the air received therein from the air inlet section, and the outer section being adapted to receive the heated air from the intermediate section and being open at its outer end whereby said heated air may be discharged therefrom through a vehicle body register to the atmosphere.
2. A heating apparatus for an automobile body comprising a tube constituting a portion of an engine exhaust conduit, and being imperforate except for four openings, two of said openings being at one end of said tube and constituting inlets for air and exhaust gases respectively, and the other two openings being at the other end of said tube and constituting outlet openings for air and exhaust gases respectively, and means open at its opposite ends to the atmosphere for conveying air from the atmosphere into the tube to be heated by the engine exhaust gases and thence from the tube to the atmosphere within a vehicle body, said means including a tubular conduit having three sections arranged end to end, the intermediate section of said conduit being entirely within and extending longitudinally of said tube, and the two other sections constituting a fresh air inlet and a hot air outlet respectively for said intermediate section and extending through the air inlet and outlet openings aforesaid in said tube, the inlet section being open at its forward end to receive air from the atmosphere to the intermediate section within said tube, and the outlet section being adapted to receive the heated air from the intermediate section and being open at its outer end to the atmosphere whereby such heated air may be discharged therefrom through a vehicle body register to the atmosphere.
3. A heating apparatus for an automobile body comprising a tube having open portions at its opposite ends attachable to an automobile exhaust manifold and exhaust muffler respectively and provided throughout substantially its entire length with a cross sectional area that is slightly larger than the cross sectional area of an ordinary exhaust conduit whereby the exhaust gases from an automobile engine may flow into and through the tube and be utilized therein as a heating medium, said tube being otherwise imperforate except for two openings one at each end of said tube, and means open at its opposite ends to the atmosphere for conveying air from the atmosphere into the tube aforesaid to be heated by the engine exhaust gases therein, and thence from the tube to the atmosphere within a vehicle body, said means including a tubular conduit having three sections, the intermediate section of said conduit being entirely within and extending longitudinally of said tube, and the other sections constituting a fresh air inlet and a hot air outlet respectively for said intermediate section and extending through the air inlet and outlet openings aforesaid in said tube, the inlet section being open at its forward end to receive air from the atmosphere and having the portion thereof within a tube extending at a substantially obtuse angle with respect to the longitudinal median line of said tube so that the exhaust gases flowing through the tube from the engine will be deflected but not materially retarded around the intermediate section within said tube to heat the air received therein from the air inlet section, and the outlet section being adapted to receive the heated air from the intermediate section and being open at its outer end whereby said heated air may be discharged therefrom through a vehicle body register to the atmosphere.
4. A heating apparatus for an automobile body comprising a tube constituting a portion of an engine exhaust conduit, and being imperforate between its ends except for four openings, two of said openings being at one end of said tube, and the other two openings being at the other end of said tube, and means open at its opposite ends to the atmosphere for conveying air from the atmosphere into the tube to be heated by the engine exhaust gases and thence from the tube to the atmosphere within a vehicle body, said means including a tubular conduit, having three sections, the intermediate section of said conduit being entirely within and extending longitudinally of said tube, and the other sections constituting a fresh air inlet and a hot air outlet respectively for said intermediate section, the inlet section extending through one of said openings at one end of the tube and being open at its forward end to the atmosphere and adapted to convey fresh air from the atmosphere to the intermediate section within said tube, and the outlet section extending through one of said openings at the other end of the tube and being adapted to

receive the heated air from the intermediate section and being open at its outer end to the atmosphere whereby such heated air may be discharged therefrom through a vehicle body register to the atmosphere.

5 In testimony whereof I affix my signature.

JAMES J. SUNDAY.
